UNITED STATES PATENT OFFICE.

ROBERT E. HUNN, OF OAKLAND, CALIFORNIA.

BUILDING-TILE AND WALL THEREOF.

1,208,785.

Specification of Letters Patent. Patented Dec. 19, 1916.

Application filed November 7, 1914. Serial No. 870,804.

To all whom it may concern:

Be it known that I, ROBERT E. HUNN, a citizen of the United States, residing at Oakland, in the county of Alameda and State of California, have invented new and useful Improvements in Building-Tiles and Walls Thereof, of which the following is a specification.

This invention relates to building tiles and walls thereof; and has for its object to provide a simple and easily manufactured tile of terra-cotta of which a number can easily be assembled to form a wall of improved strength and rigidity having perfect ventilation and increased protection against the passage of moisture therethrough. This object is accomplished by the provision of interlocking hollow tiles that can be easily and quickly laid up in double thicknesses to form a wall having continuously extending vertical flues, and in which the interlocking members on the individual tiles coöperate in various positions to permit staggering of the same, whereby to overcome the presence of transverse interstices through the wall, and means whereby the coöperating tiles may be wedged and cemented permanently in interlocked position.

In the accompanying drawing, Figure 1 is a broken perspective view of a corner of a wall formed of my improved tiles; Fig. 2 is an enlarged plan view of the tile.

Referring to the drawing, 1 indicates my improved hollow building tile. It has straight ends 2 and an outer side or face 3, the outer surface of which may be either corrugated when the tile forms the inner side of the wall, or ornamental when it forms its outer side. Its inner side or face 4 is formed with four tongues 6 all extending from said face in the same oblique direction and spaced from each other in such a manner that the tongues of an adjacent inner or outer tile will fit into the recesses 45 between the tongues of an outer or inner tile. Said tongues have a long sloping surface 7 and a short sloping surface 8 and a rounded end 9 between said surfaces. The short sloping surfaces 8 of the tongues of adjacent tiles exactly fit against each other, and the rounded end 9 of one tile exactly fits into the cavity between the short surface 8 and long surface 7 of an adjacent tile. The long surfaces 7 of adjacent tiles do not exactly fit against each other, but leave an intervening space to receive mortar 11, which, when hardened, forms a key between said tiles, preventing them from being moved longitudinally with reference to each other. For better holding the tiles together 60 each sloping surface 7 is formed a little beyond the center with a projection 12, said projections 12 of the adjacent tongues of two adjacent tiles additionally serving, in conjunction with the mortar therebetween, to hold in position the adjacent tiles. Each tile is formed with three oblique transverse walls 10 extending from the outer straight face of the tile to the three parts of the inner face in which are contained the recesses between the tongues. These three transverse walls form with the ends of the tile four cavities.

The tiles are so constructed that, when assembled to form a wall, the end of each inner tile is opposite, not to the middle of the adjacent outer tile, as has been customary to this class of devices, but to the second one of the four tongues of said adjacent outer tile. Consequently if the outer tiles are 75 placed vertically in staggered relation with each other, so that each outer tile comes exactly above the middle of the outer tile immediately below it, the end of the adjacent inner tile is not in the same vertical plane as the end of said outer tile immediately below, but is to one side thereof, and is horizontally separated therefrom by one of the mortar-filled spaces between the long surfaces 7. This arrangement prevents any 80 moisture seeping in between the outer tiles through the interstices between the inner tiles and it is of especial importance because it permits of assembling the inner and outer tiles also in staggered relation to each other vertically. For this purpose, there are provided at the bottom of the inner wall special tiles 13 of only half the height of the other tiles. The lowermost row of outer tiles extending by half its height above the lowermost row of the inner tiles, the next row of inner tiles in turn extends half its height above said row of outer tiles. It will readily be seen that if the latter method of building 90 the wall were carried out, and at the same time the juncture between the two inner tiles were exactly opposite the upper portion of the middle of an adjacent outer tile, then its lower portion would be exactly opposite to the juncture between the next two lower inner tiles, and consequently there would be a chance for moisture to seep 100 105 110

through the wall. By so forming the tile that its end must be exactly opposite to the part of a horizontally adjacent tile which is at a distance of about one-third from the 5 end of the latter, the above seepage is avoided, and at the same time the advantage is obtained that the tiles can be assembled in staggered relation vertically.

It will be observed by reference to Fig. 1 10 that the oblique transverse walls of the inner and outer tiles are in line with each other and that in all cases the juncture between two adjacent inner tiles and also between two adjacent outer tiles is immediately over one of said transverse walls. This is an additional prevention against 15 leakage through the wall between the tiles.

Two special forms of tiles are required to 20 form a corner of a wall, the tile 15 for the outside of said corner being only about three-fourths of the length of an ordinary tile, and the tile 16 at the inside of the corner being somewhat reduced in length from the ordinary tile.

25 The cavities formed by the transverse walls 10 enable vertical tie rods to extend where desired from floor to floor thus tying the entire wall to the building, each cavity containing a tie rod being filled with concrete around the tie rod. By forming the transverse members 10 obliquely, with respect to the side walls, and positioning them with regard to the overlying tiles, tie webs are provided which offer supporting means 30 of increased area for the abutting ends of said overlying tiles, as will be seen by reference to Fig. 2 where the tie webs extend diagonally of the right angular end walls of the abutting and overlying tiles.

40 I claim:—
1. A building tile having a plurality of obliquely extending tongues projecting from its vertical side face to coöperate with and overlap similar tongues on the adjacent face 45 of an oppositely disposed tile, the opposite and non-joining tongues forming between

them at their elongated sides cavities for the reception of binding material.

2. A building tile having on its vertical side face a plurality of obliquely extending 50 tongues inclined in the same direction and adapted to coöperate with and overlap similar tongues on the adjacent side face of an oppositely disposed tile, and provided with double concaved surfaces on the elongated 55 sides of the tongue to form cavities for the reception of binding material, whereby to provide an interlocking connection between opposite tiles.

3. A building tile having a series of 60 obliquely extending tongues carried on its vertical side face adapted to coöperate with and overlap similar tongues on an oppositely disposed tile, said tongues provided on their elongated sides with double concaved surfaces 65 forming a ridge where they meet, whereby to provide cavities between the co-operating tongues for the reception of binding material, the adjacent ridges coöperating to prevent relative endwise movement of 70 opposite tiles.

4. A wall comprising building tiles having 75 interlocking vertical faces, said faces comprising obliquely extending tongues upon the tiles at one side of the wall inclined in the same direction and obliquely extending tongues on the tiles at the other side of the wall inclined in a direction opposite to the first mentioned tongues and overlapping therewith, said tiles intermediate 80 their tongues being provided with opposed concaved faces to form cavities for the reception of mortar, and coöperating shoulders whereby to lock said tiles in place against endwise movement.

In testimony whereof I have hereunto set my hand in the presence of two subscribing witnesses.

ROBERT E. HUNN.
